US0D1109482S

(12) **United States Design Patent** (10) **Patent No.:** **US D1,109,482 S**
(45) **Date of Patent:** **** Jan. 13, 2026**

(54) **PORTION OF A CONVEYOR BELT**

(71) Applicant: **Ramsey Products Corporation**,
Belmont, NC (US)

(72) Inventors: **David Brian Holcomb**, Belmont, NC
(US); **Charles Stone Stalvey**, Belmont,
NC (US); **Philippe Alex Rojzman**,
Belmont, NC (US)

(**) Term: **15 Years**

(21) Appl. No.: **35/521,468**

(22) Filed: **Jun. 29, 2023**

(80) **Hague Agreement Data**

Int. Filing Date: **Jun. 29, 2023**

Int. Reg. No.: **DM/232222**

Int. Reg. Date: **Jun. 29, 2023**

Int. Reg. Pub. Date: **Jun. 28, 2024**

(51) **LOC (15) Cl.** **12-05**

(52) **U.S. Cl.**

USPC **D34/29**
